(57) **CLAIM**

What is claimed is the ornamental design for a gloves, as shown and described.

DESCRIPTION

FIG. 1 is a perspective view of a first embodiment of a gloves, showing the new design;

FIG. 2 is a top plan view thereof;

FIG. 3 is a bottom plan view thereof;

FIG. 4 is a right-side elevational view thereof;

FIG. 5 is a left-side elevational view thereof;

FIG. 6 is a front elevational view thereof;

FIG. 7 is a rear elevational view thereof; and,

FIG. 8 is a perspective view of a second embodiment thereof.

The broken lines showing a second mirror-image glove and hands in FIGS. 1 and 8 are included for the purpose of illustrating the invention in use, and form no part of the claimed design. It is understood the while a right-handed glove is illustrated in the figures, the left-handed glove is a mirror image thereof. The alternate views of the second embodiment, not shown, are understood to be substantially similar to the alternate views of the first embodiment, with the exception of the length of a sleeve portion thereof.
